(57) **CLAIM**

The ornamental design for a trigger sprayer shroud with round top, as shown and described.

DESCRIPTION

FIG. 1 is a perspective view of a trigger sprayer shroud with round top showing the new design;

FIG. 2 is a left view of the new design;

FIG. 3 is a right view of the new design;

FIG. 4 is a front perspective view of the new design;
FIG. 5 is a back perspective view of the new design;
FIG. 6 is a top view of the new design;
FIG. 7 is a perspective view of a trigger sprayer shroud with round top showing an alternative embodiment of the new design;
FIG. 8 is a left view of the alternative embodiment of the new design;
FIG. 9 is a right view of the alternative embodiment of the new design;
FIG. 10 is a front perspective view of the alternative embodiment of the new design;
FIG. 11 is a back perspective view of the alternative embodiment of the new design;
FIG. 12 is a top view of the alternative embodiment of the new design;
FIG. 13 is a perspective view of a trigger sprayer shroud with round top showing a second alternative embodiment of the new design;
FIG. 14 is a left view of the second alternative embodiment of the new design;
FIG. 15 is a right view of the second alternative embodiment of the new design;
FIG. 16 is a front perspective view of the second alternative embodiment of the new design;
FIG. 17 is a back perspective view of the second alternative embodiment of the new design;
FIG. 18 is a top view of the second alternative embodiment of the new design;
FIG. 19 is a perspective view of a trigger sprayer shroud with round top showing a third alternative embodiment of the new design;
FIG. 20 is a left view of the third alternative embodiment of the new design;
FIG. 21 is a right view of the third alternative embodiment of the new design;
FIG. 22 is a front perspective view of the third alternative embodiment of the new design;
FIG. 23 is a back perspective view of the third alternative embodiment of the new design; and,
FIG. 24 is a top view of the third alternative embodiment of the new design.

The broken-line disclosure is understood to represent portions of the article in which the claimed design is embodied, but which form no part of the claimed design.
